UNITED STATES PATENT OFFICE.

THOMAS F. FOLEY, OF WASHINGTON, DISTRICT OF COLUMBIA.

FLOAT-VALVE.

1,160,395.

Specification of Letters Patent. Patented Nov. 16, 1915.

Application filed May 21, 1914. Serial No. 840,009.

To all whom it may concern:

Be it known that I, THOMAS F. FOLEY, a citizen of the United States, residing in the city of Washington and District of Columbia, have invented new and useful Improvements in Float-Valves, of which the following is a specification.

The present invention relates to improvements in valves, and particularly to that class known as float valves which are employed in connection with tanks or closets and the like, and one of the primary objects of the invention is to arrange in connection with the float a compound leverage for operating the valve having means whereby the same may be adjusted for actuating the valve or whereby the same may be instantaneously removed from the valve to permit of the withdrawal of the valve from its casing, for repairs, etc., without interfering with the working parts of the valve-actuating mechanism.

A further object of the invention is to construct a valve casing having a post integral therewith to provide a pivot for the float rod, to connect a transverse bar with the said rod and to provide oppositely arranged pivoted arms upon the said bar which have hingedly secured thereto a substantially U-shaped yoke member that bears directly upon the valve, and to further provide an adjustable member which co-acts with the valve and with the yoke to sustain the said yoke removably connected with the valve as well as adjustably secured thereon.

With the above recited objects in view, and others which will appear as the nature of the invention is more fully disclosed, the improvement resides in the construction, combination and operative arrangement of parts set forth in the following description and falling within the scope of the appended claims.

The accompanying drawing illustrates a simple and satisfactory reduction of the improvement to practice, but it is to be understood that the showing therein is merely illustrative and that I am entitled to all such changes in scope and proportion as fall within my claims.

In the drawing: Figure 1 is a perspective view of a float valve constructed in accordance with the present invention, Fig. 2 is a central vertical longitudinal sectional view through the same, the valve casing being shown as secured to a tank, Fig. 3 is a trans-

verse section approximately on the line $x-x$ of Fig. 2, Fig. 4 is a perspective view illustrating a modified form of arranging the valve operating members upon the valve, and Fig. 5 is a vertical longitudinal sectional view through a modified form of valve-connecting and operating means.

Tank boxes for closets and the like are necessarily restricted in size; namely, because the float which controls the valve must, in order to obtain the proper leverage, be disposed a considerable distance from the valve and its casing. The float and valve thus almost entirely fill the tank or box and the water entering the box through the valve entirely surrounds the same while the half submerged float renders access to the valve almost impossible. For these reasons, when it is necessary to repair a valve, plumbers have found it desirable to entirely remove both the valve and float in order to obtain access to the valve casing or to the valve when the same requires repair. As stated as much power as possible is desired upon the float in order that the same will properly actuate the valve, and for this reason a series of levers is arranged between the float and the valve so that the power of the float will be multiplied, as much as possible, in the small space presented. The multiplication of levers adds to the complication of the structure and the separation and removal of the same to permit of the repair of the valve, as well as the rearrangement of the same after the valve has been repaired requires a great amount of time, patience and labor upon the part of the workman, such loss of time being deemed more valuable than the entire removal of the valve and the substitution of a new valve therefor. It may therefore be considered the primary object of the present invention to arrange and associate the valve-operating mechanism in such a manner that the valve may be removed from its casing for repair or for the substitution of a new valve, at a minimum amount of time and labor, and to also arrange the parts so that the same may be associated or disconnected for repairs without the absolute requirement of a person particularly skilled in the art of plumbing.

In the drawing, the numeral 1 designates an inlet pipe which is exteriorly threaded for the reception of a nut 2 which secures the pipe upon an ordinary tank; a portion 3
